GLOVE AND BOOT WARMER-DRYER FIXTURE

James G. Schenck, Castle Shannon, Pa.
(450 Miranda Road, Pittsburgh, Pa. 15234)

Filed Dec. 5, 1967, Ser. No. 9,646

Term of patent 14 years

U.S. Cl. D49—1
Int. Cl. D7—06

Fig. 2

Fig. 3

FIG. 1 is an enlarged perspective view showing the details of the fixture with portions omitted for convenience of illustration only.

FIG. 2 is a side elevation view of the fixture.

FIG. 3 is a perspective view similar to that of FIG. 1 but with the perspective taken at a different inclination.

FIG. 4 is a side-front perspective view of the fixture.

The characteristic features of my design resides in the portions shown in full lines as shown, it being understood, however, that the broken line disclosure constitutes a part of the claim.

I claim:

The ornamental design for a glove and boot warmer-drier fixture, as shown and described.
